UNITED STATES PATENT OFFICE.

CECIL FRANK SAWYER, OF TRENTHAM, NEW ZEALAND.

BOX, CASE, AND THE LIKE.

Application filed September 11, 1924, Serial No. 737,105, and in New Zealand October 10, 1923.

This invention has been devised primarily with the object of providing improved means whereby the different members used in the formation of a box or case, may be bound together in their assembled position and in such a manner that they may be freed at will and parted from one another so that they may be stacked into a comparatively small compass as with collapsible boxes or cases. The means thus used are of a nature such that they may be arranged to hold all the box members, with the exception of the lid, together in the assembled position, so that the box body may be used for packing or unpacking in the usual way, and then when the lid is placed on its top, have such lid firmly fastened in position.

The invention also provides for the fastening of the lid of an ordinary box or case, 20 the means devised in their essential features being readily adaptable for such a purpose.

In fully describing the invention, reference will be made to the accompanying drawings, in which:—

25 Figure 1 is a plan, and

Figure 2 a side elevation of a collapsible box in the assembled position and showing the banding and locking means at one end in the locked condition and at the other end in the unlocked condition.

Figure 3 is a cross sectional elevation of portion of the closed and locked box.

Figures 4 and 5 are enlarged detail views of alternative forms of the band locking means.

Figure 6 is a side elevation of an ordinary box having the means for fastening the lid only, fitted thereon, and showing an alternative form at each end.

40 Figure 7 is a plan of a further alternative form of locking band.

The invention, in so far as its use with a collapsible box or case is concerned, is adapted for use with such an article the members of which are assembled round the edges of two end pieces and are held in proper relation by means of dowel pins projecting from such edges and passing into apertures made in the other members to receive them. This arrangement is well known in connection with this class of article and needs no special description.

45 The means devised for holding the members in their assembled position consist in metallic bands, made either of hoop iron or of strong wires, that are constructed to

extend round the case near each end thereof, and are combined with means in each band whereby the ends of the band may be strained together and locked in the strained 60 position. Each band is also so constructed that the portion thereof extending across the top of the case may be turned out to free the lid when the band is slackened, and the ends of the band may then be strained and 65 locked so as to hold the other members of the case together while the lid is off.

In carrying out the invention, each band is made up of a main portion A, formed either of hoop iron as shown in Figures 1 to 70 5 of the drawings, or of strong wire, as in Figure 7, that is made to extend beneath the bottom and up both sides of the case to near the top, combined with two short portions B and C that are respectively hinge 75 jointed to the top ends of the main portion and are made of such a length as to extend in over the top of the case from each side and then to overlap one another at their respective ends. The inner ends of these two 80 portions are then pivotally attached to a metal plate D, of lever form, by pivots so disposed that when the plate lever is turned to lie continuously with the band, the ends are caused to overlap as shown by the left 85 hand band in Figure 1, and when such is turned out and round, the two ends will be pushed apart in a direction outwards from each other, as shown by the right hand band in Figure 1.

90 Thus the band may have its upper hinged portion turned sideways to clear the box lid, when in the loosened or opened out position, so that the lid may be removed and replaced. When turned out, this top hinged 95 portion may have its ends drawn together and overlapped so that the band is strained upon the bottom and sides of the box to keep such members firmly bound upon the end pieces while the box is being filled and 100 emptied. Then, when the lid has been replaced, the top hinged portion is again loosened, turned in over the lid, and then strained tight by the operation of the lever plate D.

105 The said lever plate is kept in the strained position by forming its free end with a small upwardly turned catch d that is forced under the band as the lever is turned to the straining point, so that it then engages the 110 inner edge of the band and holds the lever from turning out again. To free the lever

it is then necessary to prise the band up slightly by the aid of a suitable tool, as a screw driver, inserted beneath it, when the lever by the strain of the band thereon will 5 spring out and open up the band, as indicated by the dotted lines in Figure 3.

In some cases the lever plate may be replaced by the circular disc plate E, as shown in Figure 5, the band ends being pivoted 10 to the top of the plate at points diametrically opposite each other so that the rotation of the plate on its own axis will cause the ends to be pushed apart or drawn together and overlapped in the same manner 15 as with the lever. In such a case the disc plate is formed with apertures F therein to receive the prongs of a double pronged handle tool, by means of which the plate may be actuated in the required manner. The 20 disc plate is also formed with a turned up catch e in its edge for acting in the same manner as the catch d of the lever D.

The lever plate D may also, if desired be formed with the apertures F to receive the 25 turning tool prongs but such will not be required when the lever is made long enough to obtain the necessary straining leverage.

When the device is to be used to fasten on the lid of a box only, the top portion of the 30 straining bands have their ends pivoted to the small metal plates G let into the box sides at the necessary positions, these parts then acting in the same manner as with the collapsible box previously described. These 35 fastening means may be formed of hoop iron, as shown at the right hand end of Figure 6, or of strong wire, as shown at the left hand end of such figure, as may be desired in each circumstance.

40 If desired, the corners of the box with which the bands engage, may be protected from wear by metal corner plates H (Figure 3) affixed thereto.

I claim:—

45 1. Box and case cover fastening means formed by two metallic straps disposed to extend continuously across the top of the

said cover, at each end thereof, such straps having their respective outer ends pivotally connected to the sides of the box or case, and having their adjacent inner ends pivotally connected to the face of a turning plate at points relatively disposed thereon so that when the plate is turned in one direction the 50 said ends are drawn together and overlapped and when turned in the other direction, are moved apart, substantially as and for the purposes specified.

2. In box and case cover fastening means formed in the manner covered by claim 1, 60 constructing the said central plate with a projection on its face adapted to engage the edge of one strap and hold the plate when the plate is turned to the first mentioned 65 position, substantially as specified.

3. In boxes, cases and the like, the combination with the cover fastening means set forth in claim 1, of a band of metal adapted to encircle the two sides and bottom of the 70 box or case and to the respective upper ends of which the corresponding ends of the said fastening means are pivotally attached, substantially as and for the purposes herein specified.

4. In a collapsible box or case formed by 75 loose side, bottom and top members assembled together around end pieces, a clamping band for encircling each end of the assembled box or case, formed by a metallic band extending across the bottom and up each 80 side to near the top and two metallic straps, one of which has its outer end pivoted to one of the said band ends and the inner ends of which are pivotally connected to the surface of a plate at points so disposed that the turning of the plate in its surface plane 85 in one direction will draw the ends together with an overlapping locking action and its turning in the other direction will open out such ends, substantially as specified.

90 In testimony whereof, I affix my signature.

CECIL FRANK SAWYER.
